Patented Sept. 14, 1926.

UNITED STATES PATENT OFFICE.

GEORGE H. MORGAN, OF PHILADELPHIA, PENNSYLVANIA.

RESILIENT HEEL.

Application filed January 18, 1924. Serial No. 687,029.

The object of this invention is to provide an all-leather heel which will combine the superior wearing characteristics of leather with a resiliency comparing favorably with that obtained in the usual manner by means of rubber lifts.

The invention further resides in novel means for securing the heel to the shoe.

A preferred embodiment of the invention is illustrated in the attached drawings, in which:

Figure 1 is a view in perspective of the heel;

Fig. 2 is an inverted plan view, and

Fig. 3 is a section on the line 3—3, Fig. 2.

The advantages of resiliency in heels has been long recognized, and it has been customary to employ in obtaining this resiliency rubber or felt or similar resilient or semi-resilient material in the form of lifts, either bottom or tread lifts, or intermediate lifts. While affording general satisfaction, these heels are subject to rapid deterioration by reason of the nature of the materials employed. In the ordinary form of resilient heel, the bottom lift is made of rubber, and this heel has the disadvantage of being slippery in wet weather.

For general wearing qualities, it is desirable to form the heel entirely of leather, since this possesses a strength and durability not found in any of the materials formerly used to obtain resiliency. I have discovered means whereby I may provide an all-leather heel which possesses a resiliency comparing favorably with that obtained by means of rubber and similar materials.

In forming my heel, I employ an inner lift of leather so tanned as to make the leather soft and resilient. Although other tannages may be utilized for this purpose, I prefer to use what is known in the art as "chrome" or "mineral" tannage, since this provides an article possessing in a superlative degree all the characteristics that are desired. By using this specially prepared and resilient leather for one or more of the upper lifts, I am able without sacrificing re-

siliency to employ in the bottom or wearing lift the usual "oak" sole-leather whose hardness and wear-resisting characteristics surpass other types.

In Figure 1, I have illustrated a heel or the two lower lifts thereof made in accordance with the above description. The bottom or tread lift, preferably of hard tanned leather such as "oak," is designated by the reference numeral 1, and to this is suitably secured, as by cement, an upper lift 2 of soft tanned leather such as "chrome." These lifts may be of any thickness desired, and there may be in the heel still other lifts (not shown) and consisting either of the hard tanned or soft tanned leather.

In order to secure the heel to the shoe or to the upper lifts in such manner as to preserve to the full extent the resiliency of the soft lift 2, I prefer to perforate the bottom lift 1 for reception of the securing means, these perforations 3 extending completely through the bottom lift, as shown in Fig. 3, so that the heads of the nails 4, by means of which these parts are secured in the heel, bear against the soft leather lift 2. I have discovered that when the nails or tacks are driven directly through the bottom lift, there is a tendency to compress the inner soft leather lift or lifts and, in part, to destroy their resiliency. This tendency, however, I entirely eliminate by the device hereinbefore described, since obviously although the nails 4 may slightly compress the soft leather upper lift 2 at the points where the heads bear against this lift, the greater area of the lift is left uncompressed and capable of exerting a cushioning effect to the full extent of its ability.

I claim:

1. A heel comprising a bottom lift of hard-tanned leather and an inner lift of soft-tanned leather.
2. A heel comprising a bottom or wearing lift of hard tanned oak leather and an inner cushioning lift of soft tanned chrome leather.

GEORGE H. MORGAN.
